DRAWER GUIDE

Carl F. Wolters and Niels Yde Andersen, Kenmore, N. Y., assignors to Remington Rand Inc., a corporation of Delaware

Application June 8, 1943, Serial No. 490,052

3 Claims.

(Cl. 45-77)

This invention relates to improvements in drawer guides.

The invention comprehends the provision of a drawer guide or suspension for correspondence and similar filing cabinets providing a construction using a minimum of metal and providing long wearing qualities; using a minimum of space for keeping the cabinet size as small as practicable to save floor space; having easy running qualities; having the guide or suspension tracks interengaged in assembled relation for uniform guiding of the tracks in operation; having an arrangement for convenient removal of the drawer by merely lifting it from the suspension in extended position with the intermediate track arranged for disengagement from its operative position by slightly raising the front end; having the means holding the tracks in interengaged longitudinally slideable relation also forming stops for limiting the relative longitudinal movement of one track relative to the other; and having the guiding and stop means also cooperating to detachably retain some of the metal bearing sections in assembled relation.

In the drawings:

Fig. 1 is a vertical longitudinal cross-section through the upper end of a cabinet with its drawer shown in closed position and having portions broken away and shown in section for illustrating the construction and assembly of the drawer guide.

Fig. 2 is a fragmentary view with portions broken away and shown in section illustrating the drawer guide shown in Fig. 1 in the extended position.

Fig. 3 is an enlarged vertical cross-section taken on line 3—3 of Fig. 1.

Fig. 4 is an enlarged vertical cross-section taken on line 4—4 of Fig. 1, illustrating only one drawer guide member and fragmentary portions of the cabinet and drawer associated therewith.

Fig. 5 is an enlarged cross-section similar to Fig. 4, taken on line 5—5 of Fig. 1.

Fig. 6 is an enlarged fragmentary view looking at the front end of the casing track from the inside of the cabinet illustrating the intermediate track with the front end tilted upwardly in partially withdrawn position where it can be disengaged from its interlocked relation with the casing track.

Fig. 7 is an enlarged fragmentary longitudinal section through the front end portion of an intermediate track illustrating how the stop members at the front end of the intermediate track cooper-

ate to retain a metal bearing channel in assembled relation on the track.

Figs. 8 and 9 are transverse cross-sections through the upper edge of a casing track showing the manner of applying a metallic bearing strip in position so that it is effectively retained in the channel portion of the track.

Fig. 10 is a detail plan view of the bearing roller assembly between the intermediate and casing tracks.

The drawer guide forming the present invention is designed particularly for manufacture from wood or other similar non-metallic material to provide a long-wearing, easy-running drawer suspension using metal only for bearing portions.

The cabinet or casing structure has a top wall 1, a side wall structure 2, a rear wall 3, the bottom wall not being shown and the front of the casing having a plurality of openings for receiving a drawer through each opening formed by striker bars 4. 5 indicates the front of one drawer in Fig. 1 having side walls 6 attached thereto and connected together at the rear by rear wall 7. The drawer bottom 8 is illustrated in Fig. 3. The side wall structure 2 may be formed of a suitable side panel and inside framing members such as illustrated in the drawings, all of which are designated by the numeral 2 in view of the structure being of conventional design. When a drawer is in the closed position in the cabinet or casing, drawer front 5 closes the opening for the drawer at the front of the casing, in the manner illustrated in Fig. 1.

The drawer suspension forming the present invention is formed of casing, drawer and intermediate tracks mounted on bearing rollers for substantially free longitudinal movement in a manner so that the drawer may be moved between positions where it is supported in front of the cabinet and in fully housed position within the cabinet.

The drawer guide or suspension has two sets of track members, one at each side of the cabinet formed in an opposite manner to each other, but otherwise of duplicate construction. It is therefore, only necessary to describe the drawer guide structure at one side of the cabinet, similar numerals being used on corresponding parts of the structure at both sides of the cabinet, from which it should be clear how the drawer guide or suspension is constructed and operated.

The drawer suspension comprises upper and lower track members 10 and 11, respectively, mounted in spaced parallel relation on side walls 2, as shown in the drawings. Casing tracks 10 and

11 are made of wood or other similar non-metallic material. Casing tracks 10 and 11 have longitudinal channels extending throughout the length thereof in the lower and upper faces respectively, as indicated at 12 and 13 respectively. Channel 12 is unobstructed throughout its length. Channel 13 of lower casing track 11 has a stop member 14 in the form of a block rigidly secured in groove 13 at the rear end thereof. A similar stop member 15 is mounted on track 11 at the front end thereof in slot 13.

An intermediate stop 16 in the form of a block is engaged in channel 13 with member 11 and is removably secured in channel 13 by a screw 17, as shown in dotted lines, Fig. 1. Stop member 16 is located at a spaced position rearwardly of the front end of casing track 11 for limiting the travel of the bearing rollers in channel 13 as well as limiting the outward movement of the intermediate track in a manner that will be hereinafter described.

A sheet metal bearing strip 18 extends between stops 15 and 16 and is positioned in the bottom of channel 13 in fixed relation. This strip is applied in track 11 in the manner shown in Figs. 8 and 9. Strip 18 is formed in a curved shape in cross-section as shown in Fig. 8, so that the edges are a distance apart that is less than the distance between the side walls of track 11 forming channel 13. Strip member 18 is inserted into channel 13 into the position shown in Fig. 8 and then a suitable forming roller is applied to the upper surface of bearing strip 18 to flatten the strip out against the bottom of channel 13 whereupon it takes a position substantially like that shown in Fig. 9 where strip 18 is arranged in flat relation in the bottom of channel 13 with the side edges embedded in the material of track 11 in the manner shown in Fig. 9. This rigidly and effectively retains bearing strip 18 in position against movement relative to track 11 without other securing means. The ends of bearing strip 18 terminate adjacent the ends of stops 15 and 16 as clearly shown in Figs. 1 and 2.

An intermediate track 20 is formed of a strip of wood having longitudinally extending channels 21 and 22 in the upper and lower edges thereof, respectively. A bearing strip 23 is mounted in fixed relation in channel 22 in the lower edge thereof so as to extend from a point at about the center of the track forwardly to a position terminating in spaced relation from the front end as shown in Figs. 1 and 2. Bearing strip 23 is positioned and secured in intermediate track 20 in the same manner disclosed in Figs. 8 and 9 and described in connection with the mounting of bearing strip 18. Bearing strip 23 is opposed to bearing strip 18 so that fiber bearing rollers 24 will engage bearing strips 18 and 23 and support intermediate track 20 in spaced relation above casing track 11 for rolling movement on the pair of rollers 24. A substantially S-shaped wire axle member 25, see Fig. 10, has rollers 24 mounted on opposite ends thereof for rotation so that axle member 25 causes rollers 24 to operate as a pair during engagement between bearing strips 18 and 23 for providing a roller bearing supporting intermediate track 20 on lower casing track 11. A guide and stop member 26 is seated in channel 22 at the rear end and on the bottom edge of intermediate track 20 as shown in Fig. 1, where it is rigidly secured to track 20. The lower edge of guide and stop member 26 engages and rides in channel 13 of lower casing track 11 and has cushioning pads 27 on opposite ends thereof for

engagement with stop blocks 14 and 16 respectively, in arresting the forward and rearward movement of intermediate track 20.

A strip of sheet metal forming bracket 28 is folded into U-shape in cross-section and mounted to straddle the rear end of intermediate track 20 with one end extending upwardly above the upper edge thereof, to rotatably support bearing roller 29, formed of fiber, on a metallic pin or axle 30 carried by bracket 28. Bracket 28 is mounted on intermediate track 20 to support bearing roller 29 in such relation to the position of upper and lower casing tracks 10 and 11 that roller 29 will be seated in channel 12 of casing track 10 when intermediate track 20 is in parallel relation to tracks 10 and 11 with bearing strip 23 having bearing contact and support on rollers 24. Guide and stop block 26 will ride in channel 13 of casing track 11 in the assembled position of intermediate track 20 in the manner shown in Figs. 1, 2, 4 and 6. In this assembled position of intermediate track 20 it can be moved forwardly and rearwardly between its opposite limits of movement relative to casing tracks 10 and 11 and is retained against sidewise disengagement from the casing tracks through roller 29, guide block 26 and rollers 24 engaging in the respective channels.

The forward upper edge portion of intermediate track 20 has a stop block 31 rigidly and permanently mounted therein in the same manner as blocks 14 and 15 are mounted in casing track 11. The rear end of stop block 31 is recessed as indicated at 32 in Figs. 1 and 7, to receive and retain the forward end of a metallic roller bearing support 33. A detachable stop block 34 is mounted in the forward central portion of intermediate track 20 in channel 21, as shown in Figs. 1 and 7. This stop block 34 is formed of wood and is removably secured in position by a wood screw 35, Fig. 7, threaded into the adjacent portion of intermediate track 20. The forward end of stop block 34 is recessed as indicated at 36, Fig. 7, for receiving the rear end of bearing support 33 for cooperation with stop block 31 in retaining bearing support 33 in assembled position on the upper forward edge of intermediate track 20.

Metallic roller bearing support 33 is formed of channel shape in cross-section to fit in channel 21 of intermediate track 20 for receiving and providing a bearing surface along the bottom of channel 21 for bearing roller 37. The upper edge portions of bearing support 33 are formed to provide inwardly facing retaining channels 38 for receiving the ends of axles 39 carried by roller 37. Retaining channels 38 cooperate with the free ends of axle 39 to retain roller 37 assembled with bearing support 33 so that they may not be accidentally disengaged from intermediate track 20. Roller 37 is assembled in bearing support 33 by inserting the ends of the axle into the retaining channels 38 through the open end thereof which is normally closed in the assembled relation of this bearing support in intermediate track 20 by stop blocks 34 and 36.

The rear end of intermediate track 20 is provided with a stop block 40 rigidly and permanently mounted in the rear end of channel 21. A cushioning member 42 is mounted on the forward end of stop block 40 as shown in Fig. 1 for arresting the rearward movement of the drawer track and the drawer in a manner that will be herein-after described.

Drawer tracks 45 are mounted one on each of the drawer side walls 6 in the manner shown in the drawings, particularly Figs. 1, 3 and 4, for as-

sembly and operation with the drawer suspension structure at each side of the cabinet constructed as above described. Each drawer track is formed of a strip of wood having a rectangular cross-section with a longitudinally extending channel in the lower edge indicated at 46. A guide block 47 is secured in rigid permanent relation on the rear upper end of drawer track 45 in the manner shown in Figs. 1 and 3. Drawer track 45 is engaged, in assembled relation with the drawer guide structure, between the upper edge of intermediate track 20 and the lower edge of upper casing track 10 with guide block 47 slidably engaged in channel 12 of casing track 10.

A guide and stop block 50 is mounted on the lower rear end of drawer guide 45. Guide and stop block 50 is seated in channel 46 at the rear end thereof in a position below guide block 47 and slightly forward thereof, as shown in Figs. 1 and 2, so that the lower edge will slidably fit and freely slide in channel 21 of intermediate track 20 in a position to engage with cushion 42 at the rear end of its movement in channel 21 so that stop block 40 will limit the rearward movement of drawer track 45 relative to intermediate track 20. Stop and guide block 50 will also have the forward end thereof engage stop block 34 at the forward end of the relative movement of drawer track 45 with respect to intermediate track 20 when the drawer is moved to its forwardly extended position out of the cabinet, as illustrated in Fig. 2.

A bearing strip 51 formed of sheet metal, is mounted in the forward central portion of channel 46 in drawer track 45 for bearing engagement on roller 37 so that the weight of the drawer and its contents will be applied through drawer track 45 to intermediate track 20 through roller 37 and the bearing contact of bearing strip 51 thereon. Bearing strip 51 is mounted in the bottom of channel 46 and is applied in position, in the manner that bearing strip 18 is applied to casing track 11, as illustrated in Figs. 8 and 9 and described above. Wood screws 52, as shown in Fig. 4, or other equivalent means, are used to secure drawer tracks 45 rigidly to side walls 6 of the drawer.

The cabinet and drawers are constructed so that the drawer will occupy substantially the entire depth of the cabinet from front to rear, as shown in Fig. 1 for example, in order to avoid waste space in the cabinet to the greatest extent that is practically possible. Therefore, the drawer in closed position will have the rear end terminate in close adjacent relation from the inside face of rear wall 3, as shown in Fig. 1. The upper and lower casing, intermediate and drawer tracks are constructed and proportioned to fit within the cabinet and extend from the front to the rear ends thereof, in the manner shown in Fig. 1, with the parts so arranged that in the withdrawn position the drawer will be supported in substantially fully extended position in front of the cabinet. The drawer and intermediate tracks are illustrated in the fully extended position relative to the upper and lower casing tracks in Fig. 2.

The several tracks are dimensioned and arranged so that drawer track 45 is positioned above intermediate track 20. Drawer track 45 and intermediate track 20 are assembled in adjacent relation and engaged between upper and lower casing tracks 10 and 11 respectively, so as to fill the space therebetween and be arranged in interengaged relation with each other and the upper and lower casing tracks for free forward and rear-

ward movement of the drawer and intermediate tracks relative to each other and the casing tracks.

Drawer and intermediate tracks 45 and 20 respectively, are arranged to operate in substantially parallel relation to each other and casing tracks 10 and 11. There is a slight tilting of drawer track 45 relative to intermediate track 20 in the operation of the drawer guide due to the clearances between the several tracks and the intervening and interengaged supporting rollers, stop and guide blocks.

Whenever the center of weight in the drawer is forward of roller 37 the front end of the drawer will move downwardly about roller 37 as a fulcrum, bringing guide block 47 upwardly against the lower edge of upper casing track 10 in channel 12 for sliding engagement therewith. The weight of the drawer is directly transmitted through roller 37 to intermediate track 20. Since bearing member 33 and bearing strip 51 have roller 37 engaged therebetween at all times in the operation of the drawer guide, wear in the drawer guide structure is applied and absorbed by roller 37 and these metallic bearing members and supports so as to build a long-wearing life into this part of the drawer guide structure.

In forward movement of the drawer and intermediate tracks in the operation of the drawer from a closed position, as shown in Fig. 1, to the open position shown in Fig. 2, roller 37 will travel from the position illustrated in Fig. 1 to that shown in Fig. 2. It moves from a position adjacent stop block 34 forwardly in the opening movement of the drawer until the drawer reaches the open position shown in Fig. 2 where it is adjacent stop block 31 when stop and guide block 50 engages stop block 34 to limit further forward movement of the drawer relative to intermediate track 20. In this position of the parts the weight of the drawer causes the front end to fulcrum about roller 37 for movement in a downward direction, while the rear end of the drawer tends to move upwardly and maintains guide block 47 in engagement with casing track 10 when the greater portion of the weight in the drawer is disposed forwardly of rollers 37.

In this operation of the drawer guide intermediate track 20 moves from the rearmost position, as shown in Fig. 1, to the position shown in Fig. 2, where the forward end extends outwardly from the front of the cabinet so that about half of intermediate track 20 projects in front of the cabinet. The intermediate track 20 is operable independently of the motion of drawer guide 45 between its outer and inner limits of movement. The weight of the drawer transmitted thereto by the drawer track through roller 37 provides for the support of the weight of the drawer by intermediate track 20 on the forward end portion thereby tending to rock intermediate track 20 about bearing rollers 24 to move the front end in a downward direction and the rear end in an upward direction. This will cause bearing roller 29 to have bearing engagement throughout the major portion of the travel of the intermediate track with upper casing track 10 at the bottom of channel 12 therein.

The weight of the drawer will be transmitted through the drawer track to intermediate track 20 and then through rollers 24 to lower casing track 11. Rollers 24 will always be in bearing contact in the operation of the drawer guide between bearing strips 18 and 23. Rollers 24 in the housed position of the drawer will be nor-

mally located adjacent stop 16, as shown in Fig. 1, and will travel forwardly on bearing strip 18 of lower casing track 11 to a position adjacent the front end of casing track 11 and front stop block 15, as shown in Fig. 2.

Whenever the weight in the drawer is such that the center of gravity passes to the rear of roller 37 and rollers 24, then the rear ends of drawer guides 45 and intermediate track 20 will drop downwardly about rollers 37 and 24 as a fulcrum until guide and stop blocks 26 and 50 respectively, support the rear ends of the tracks one on another and lower casing track 11, in the manner shown in Fig. 1. This condition will occur when the drawer, drawer track 45 and intermediate track 20 approach the inner end of the movement of the drawer toward housed position in the cabinet and particularly when the drawer is filled with correspondence to the rear end thereof. A partial forward movement of the drawer toward its open position will move the center of gravity to a position in front of roller 37 so as to produce the relation between the drawer, intermediate and casing tracks where the front ends of the drawer and intermediate tracks are moved downwardly to the limit of clearance. This condition varies as the load in the drawer varies because papers filed in the drawers of filing cabinets are always placed at the front.

In operation the weight in the drawer in being transmitted to intermediate track 20, will normally cause the intermediate track to move outwardly with the drawer in the initial outward movement of the drawer toward open position until stop and guide block 26 engages stop block 16. Then the drawer is further moved toward and to its outermost position on intermediate track 20 while it remains stationary at its outermost limit of movement. The frictional relation between the drawer track and intermediate track 20 and the manner of distributing the weight of the drawer through these tracks to casing tracks 10 and 11 will normally obtain the outward movement of the intermediate track with the drawer track as above described, although a change in condition of friction and weight position or center of gravity in the drawer may obtain only partial outward movement of intermediate track 20 with the drawer or none at all, before guide and stop block 50 engages stop 34 and positively moves intermediate track 20 to its outermost position.

Guide block 47, drawer track 45, guide and stop block 50 and roller 37 operating in the channels of upper casing track 10 and intermediate track 20 cooperate to interlock drawer track 45 and intermediate track 20 between upper and lower casing tracks 10 and 11 so that they cannot become disengaged in the normal operation of a drawer into and out of the housed position in the cabinet. Guide and stop blocks 26, stop blocks 15 and 16 and rollers 24 running in channels 13 and 22, also cooperate in this interlocking action for retaining the drawer and intermediate tracks engaged between the casing tracks so that they have only forward and rearward movement. The proportioning and arrangement of the parts provide for free and easy operation of the drawer between its forward and housed positions relative to the casing or cabinet.

Should it be desired to remove a drawer from the cabinet, it is necessary to move the drawer to the open position shown in Fig. 2. Then, by elevating the front end of the drawer to disengage drawer tracks 45 from roller 37 and stop blocks 31 and 34, stop and guide blocks 50 will then sup-

port the rear end of the drawer so that guide block 47 will move downwardly away from casing track 10 out of channel 12. The drawer can then be lifted so that stop block 50 will clear stop block 34 and the drawer removed from support on intermediate tracks 20.

Should it then be desired to disengage and remove an intermediate track 20 from assembly with casing tracks 10 and 11, it is necessary to then tilt the front end of intermediate track 20 upwardly to the position shown in Fig. 6. This has a similar result to the tilting of the drawer track in disengaging bearing roller 29 from channel 12 of casing track 10. Then intermediate track 20 may have the upper edge tilted inwardly to disengage roller 12 from casing track 10 through sidewise tilting motion, whereupon the intermediate track may be lifted out of engagement with lower casing track 11 to completely disengage and remove it from the cabinet.

In assembling the intermediate track with the casing tracks, the above operation is reversed in a manner that should be clearly apparent from the above description. The assembly of the drawer with the drawer tracks should also be clear as the operation in assembly is the reverse of the removal operation above described.

By reference to Figs. 3 to 5 it will be seen that this drawer guide construction provides for the use of wood in providing a most efficient, easy-operating and long-wearing drawer guide construction that utilizes little space thereby saving floor space. Actual tests in the operation of the drawer guide constructed as shown in the drawings have produced information showing that it will outwear most of the previously known drawer guide structures made of metal, as well as the previous wood types. The drawer guide operates with an ease comparable with metal drawer guides of the type previously known in the art as well as previously known drawer guides made of wood.

The invention claimed is:

1. A drawer guide comprising upper and lower spaced parallel casing tracks formed with longitudinally extending channels in the facing edges, stop blocks rigidly mounted at the forward and rear ends in the channel of said lower casing track, an intermediate stop block mounted in the channel on said lower casing track in the forward central portion in spaced relation to said stop block at the forward end thereof, a bearing strip mounted in said channel in the lower casing track and extending between said intermediate stop block and the stop block at the forward end thereof, bearing rollers engaged in the channel of said lower casing track on said bearing strip, an intermediate track formed with longitudinal channels in the upper and lower edges and supported on said bearing rollers, a bearing strip mounted in the lower channel in said intermediate track engaging said bearing rollers, a bracket mounted on the rear end of said intermediate track and extending above the upper edge thereof into proximity to the upper casing track, a bearing roller rotatable in the upper end of said bracket having bearing contact in the channel of said upper casing track, a guide and stop block mounted on the lower edge at the rear end of said intermediate track in the channel therein and having the lower edge slidably engaged in the channel between the intermediate and rear stop blocks on said lower casing track, said intermediate track having stop blocks at the front and rear ends of the upper edge thereof, an intermediate stop block mounted on the upper forward central portion

of said intermediate track, a bearing support mounted on the upper edge of said intermediate track between the front and intermediate stops thereon, a bearing roller mounted on said bearing support, a drawer track having a longitudinal channel in the lower edge engaged between said intermediate track and said upper casing track with the stop blocks on the upper edge of said intermediate track engaged in the channel in said drawer track, a guide block on the upper rear end of said drawer track slidably engaged in the channel in said upper casing track, and a guide and stop block on the lower rear end of said drawer track slidably engaged in the upper channel in said intermediate track whereby said stop blocks, guide and stop blocks and bearing rollers on said tracks cooperate in engaged relation in the channels in adjacent tracks for supporting a drawer attached to said drawer tracks for free limited movement into and out of a compartment in a casing and normally retain all of said tracks in interengaged relation.

2. A drawer guide comprising upper and lower spaced parallel casing tracks having longitudinally extending channels in the facing edges, an intermediate track formed with longitudinal channels in the upper and lower edges thereof engaged between the upper and lower casing tracks, bearing rollers between said intermediate and lower casing tracks for supporting said intermediate track on said lower casing track for free longitudinal movement, said rollers engaging in said channels, a plurality of stop and guide blocks mounted on the upper and lower edges of said intermediate track and said lower casing track projecting into the channel in the adjacent track for cooperation to retain said intermediate track slidably engaged between said upper and lower casing tracks, and a drawer track having a channel formed in the lower edge thereof slidably engaged between said intermediate track and the upper casing track and receiving the stop and guide projections on the upper edge of said intermediate track in the channel therein for cooperation in retaining said drawer and intermediate tracks in interengaged longitudinally slidable relation between said upper and lower casing tracks, a bearing support mounted on the upper forward edge of said intermediate track, said bearing support having a channel shape in cross-section and formed with retaining channels on opposite upper side edges facing each other, a bearing roller mounted in said bearing support having projecting axle portions engaged in said

retaining channels for retaining said bearing roller in attached relation on said intermediate track, said bearing roller engaging in the channel of said drawer track for supporting said drawer track on said intermediate track, and a pair of guide blocks mounted on the rear upper and lower edges of said drawer track for engagement in the adjacent channels in said upper casing track and said intermediate track for cooperation in retaining said drawer and intermediate tracks in assembled relation between said upper and lower casing tracks and guiding said drawer and intermediate tracks in movement between the open and closed positions of a drawer carried by said drawer track.

3. A drawer guide comprising upper and lower spaced parallel casing tracks, an intermediate track slidably mounted between said upper and lower casing tracks and having roller bearing support with the lower edge of said intermediate track adjacent said lower casing track, said intermediate track having a channel formed in the upper edge thereof, a stop block mounted on the front upper edge of said intermediate track having a notch formed in the rear end thereof in said channel, a bearing support mounted in the front end of said channel having the forward end thereof engaged in the notch in said stop block, an intermediate stop block detachably mounted in the channel in the upper edge of said intermediate track having a projecting portion engaging over the rear end of said bearing support and cooperating with the front stop block for retaining said bearing support in engaged relation on the front end of said intermediate track, a bearing roller mounted on said bearing support for movement between said front and intermediate stop blocks, a drawer guide having a longitudinal channel in the lower edge thereof receiving said bearing roller in said channel with said drawer guide engaged between said intermediate and upper casing tracks for free sliding movement on said bearing roller, and stop and guide blocks on the rear end of said drawer track slidably engaged with the upper casing track and in the channel of said intermediate track respectively, for cooperation with the bearing roller in guiding said drawer track in movement toward and from open position of a drawer carried by said drawer track relative to a casing and cooperating to hold said drawer and intermediate tracks in slidably interengaged relation for limited movement.
